UNITED STATES PATENT OFFICE

105,260

DESIGN FOR AN AIR PROPELLER FOR FANS

Paul M. Brannan, St. Louis, Mo., assignor to The Emerson Electric Mfg. Co., St. Louis, Mo., a corporation of Missouri

Application June 5, 1937, Serial No. 69,690

Term of patent 14 years

To all whom it may concern:

Be it known that I, Paul M. Brannan, a citizen of the United States, residing at St. Louis, State of Missouri, have invented a new, original, and ornamental Design for Air Propellers for Fans, of which the following is a specification, reference being had to the accompanying drawing, in which

Figure 1 is a top plan view of an air propeller constructed in accordance with my invention.

Figure 2 is a front elevation of the air propeller shown in Figure 1.

The characteristic features of the air propeller constructed in accordance with the present invention comprises a hemispherical shaped hub having attached thereto blades of a configuration and in the manner shown in the accompanying drawing.

I claim:

The ornamental design for an air propeller for fans as shown and described.

PAUL M. BRANNAN.
